UNITED STATES PATENT OFFICE

ALFRED HOLTER, OF BREVIK, NORWAY

TRAVELER'S TOILET CASKET

Application filed March 4, 1930, Serial No. 433,105, and in Norway June 25, 1929.

My invention relates to improvements in travelers' toilet caskets.

It is a well known fact that the mirrors of railway cars and hotel rooms are often placed so unsuitably in relation to the light, that it is next to impossible to use them for shaving. It is often also difficult to get the usual mirrors for traveling use placed suitably in relation to the source of light.

10 The object of my invention is to provide a toilet casket, arranged in such a manner as to avoid this difficulty. In this toilet casket the shaving mirror, which is in known manner fitted on the inside of its lid, is arranged 15 in such manner that the lid may be swung with its inside out and be adjusted at any angle suitable for shaving or other toilet purpose. The casket is also fitted with means for the 20 fastening of a strap, arranged to be fitted to the body of the person using it, in such manner that he may have both hands free for the shaving operation.

A toilet casket or case according to my invention is illustrated in the accompanying 25 drawings, in which:

Fig. 1 is a plan view of the casket, with closure parts omitted.

Fig. 2 is a side view and

Fig. 3 is an end view of the same.

30 Fig. 4 is a plan view of a loose box, arranged to be locked to the toilet casket by aid of the same lock bar which also serves as a holder for the mirror.

In the drawings 1 is the casket, which may 35 for instance be pressed from sheet metal and coated with nickel or the like. 2 is a locking bar, reaching across the whole length or width, respectively, of the casket. One end of this bar 2 is hinged to the side wall of the casket at 3, its opposite end having hinged connection 4 with the lid 5 of the casket. This lid is provided with a mirror 6 on the inside. The hinge part 4 is provided with a 40 depending locking tongue 7, adapted to grip a lock projection 8, fitted on the outside of the wall of the casket.

The sides of the casket are provided with loops 9 for fastening on to it a strap (not shown), by aid of which the casket may be 45 fastened to the body. Before this is made,

the contents of the casket should preferably be removed. For this purpose there is fitted a loose plate 10 into the casket. This plate is provided with two or more side flanges (not shown), by aid of which the plate may easily 55 be lifted out of the casket. This plate is also provided with apertures with flanges, serving to keep the various parts of the contents in place.

When the mirror in the lid of the casket 60 is to be used as a shaving mirror, this may be arranged by placing the lid 5 in the position illustrated in dot and dash lines in Fig. 2, in which the mirror is propped up against the edge of the casket and is used as a table 65 mirror.

Or I may swing the mirror entirely out about the hinges 3 and 4 after having first 70 emptied the casket by lifting out the plate 10. The empty casket is fastened to the body 70 by aid of a strap inserted in the loops 9, and the mirror is adjusted in a position suitable for shaving by aid of the hinges 3 and 4.

It may also be convenient to make the lid 5 with its mirror 6 turnable about a bolt (not 75 shown) at right angles to the hinge 4 in order to be able to adjust the mirror at any desired angle.

The bar 2 which reaches right across the 80 length (or width) of the casket may also be utilized for locking a loose toilet box, for instance for soap, brushes or the like, on to the top of the casket 1. This box is suitably divided into two separate containers 12, 13 (Figs. 3 and 4), having a common bottom 85 plate 14. Between the two containers 12, 13 is an intermediate space, covered only by the bottom plate 14, and which is straddled by the bar 2, thus locking the box 12, 13, 14 to the casket 1.

In the drawings is by way of example shown a contents of brushes, shaving utensils and the like, but of course this may be varied according to circumstances.

Claims:—

1. A toilet casket including a body, a closure therefor including a lid and a locking bar having one end hinged to one side of the body and the opposite end detachably connected to the opposite side of the body and 100

pivots connected to the adjacent side of the lid so that when the bar is raised the lid will be swung inside out, substantially as and for the purposes set forth.

5 2. A toilet casket including a body, a closure therefor including a locking bar having one end hinged to one side of the body and the opposite end detachably connected to the opposite side of the body, a lid hinged to the detachable end of the bar and normally held

10 in covering position on the body by the bar and adapted to be swung inside out when the bar is raised, and a mirror carried by the inside of the lid, substantially as and for the purposes set forth.

15 3. A toilet casket including a body, a lid therefor, a mirror fitted on the inner side of the lid, a locking bar hinged to one side of and extending across the body and having its outer free end hinged to the adjacent edge of the lid so as to permit the lid being swung inside out about the free end of the locking bar, and cooperative locking means on the body and free end of the bar.

20 4. A toilet casket as claimed in claim 1, and in combination therewith, a separate loose toilet box arranged to be locked to the top casket by said locking bar.

25 5. A toilet casket as claimed in claim 3, and in combination therewith, a separate loose toilet box having a depressed central portion and adapted to be arranged on the casket in such manner that the locking bar straddles the depressed part and releasably holds the box on the casket.

30 In testimony whereof I have signed my name unto this specification.

ALFRED HOLTER.
